UNITED STATES PATENT OFFICE.

JOHN GIBSON, JR., OF MIDDLETOWN, OHIO, ASSIGNOR TO THE WRENN PAPER COMPANY, OF MIDDLETOWN, OHIO, A CORPORATION OF OHIO.

DESIGN FOR BLOTTING-PAPER.

No. 39,544.

Specification for Design.

Patented Sept. 15, 1908.

Application filed September 5, 1907. Serial No. 391,539. Term of patent 3½ years.

To all whom it may concern:

Be it known that I, JOHN GIBSON, Jr., a citizen of the United States, residing at Middletown, in the county of Butler and State of Ohio, have invented a new, original, and ornamental Design for Blotting-Paper, of which the following is a specification.

This invention relates to a new and ornamental design for blotting paper, the essential characteristics of the design being illustrated in the accompanying drawing, wherein,

The figure is a plan view of a piece of blotting paper embodying the features of the design.

Referring to the drawing, it will be observed that the design consists of a plurality

of regularly spaced longitudinal and transverse lines which divide the surfaces of the blotting paper into a plurality of uniform squares, each square inclosing a plurality of squares of gradually decreasing size. The arrangement of the design upon the blotting paper being such as to give a general Mosaic appearance to the same.

I claim:

The ornamental design for blotting paper, as shown and described.

JOHN GIBSON, JR.
